UNITED STATES PATENT OFFICE

HENRY WAGNER, OF CHICAGO, ILLINOIS

SEWER CHECK

Application filed December 29, 1928. Serial No. 329,269.

The invention relates to means for preventing the flooding of basements, cellars and analogous low places having connection with a sewerage system when there is an abnormal rise of water, or increase in the pressure from heavy rain, or a thaw in winter when the ground is covered with snow and ice.

The invention consists of a check adapted to be located in the length of the soil pipe connecting with the sewer and comprising a frame, or casing, and a float controlled valve which automatically closes upon an abnormal rise of water to prevent back flow and a flooding of the premises.

While the drawing illustrates a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawing hereto attached, in which:—

Figure 1 is a central, longitudinal sectional view illustrative of an embodiment of the invention.

Figure 2 is a transverse sectional view on the line 2—2 of Figure 1 looking in the direction of the arrows.

Figure 3 is a fragmentary sectional view on the line 3—3 of Figure 2.

Figure 4 is a sectional view similar to Figure 1 illustrating a modification and the addition of adjunctive parts whereby to vent the attachment and to draw off water from the house end of the sewer and discharge the same into the sewer end when the valve is closed by an abnormal rise of water.

Figure 5 is a horizontal sectional view on the line 5—5 of Figure 4.

Figure 6 is an enlarged detail sectional view on the line 6—6 of Figure 4.

Corresponding and like parts are referred to in the following description and designated in the several views of the drawing by like reference characters.

The numeral 1 denotes the usual soil pipe

which connects the premises to be drained with the sewer. In accordance with the present invention the check is located in the length of the pipe 1 and comprises a frame or casing and a float controlled valve. When 55 the check is constructed to be installed in sewers in service the frame or casing is constructed substantially as shown to be clamped against a side of the pipe 1, but when constructed to be applied to new sewers the frame 60 or casing will be of such formation as to be set into the length of the soil pipe without necessitating the breaking away or removal of the side portion of the pipe for the installation of the check.

In the present instance the frame or casing comprises a body 2 and a cover 3 which is bolted or otherwise secured to the body to close the top thereof and admit of ready access thereto for any desired purpose. The 70 bottom of the body 2 is open to admit of communication being established between the sewer pipe 1 and the interior of the frame or casing. The bottom edge of opposite end walls of the frame is depressed or curved to conform to the curvature of the sewer pipe 1 to fit the same closely. The bottom edge of the side walls of the frame is bevelled for a like purpose, as indicated most clearly in Figure 2 of the drawing.

Flanges 4 project outwardly from the end walls of the frame or casing and curve transversely to conform to the curvature of the pipe 1. Cement 5 or other suitable material is interposed between the flanges 4 and the adjacent side of the pipe 1 to insure the formation of a tight joint. Lugs 6 project laterally from the sides of the frame or casing and receive the threaded ends of straps 7 which extend beneath the pipe and have nuts 8 threaded upon the projecting ends to clamp the frame to the top side of the pipe 1.

A gate valve 9 is snugly fitted against the inner side of an end wall of the frame or casing and its lower portion is curved to conform to the inner diameter of the sewer pipe 1. Guides 10 applied to the inner side of the end wall engage vertical edge portions of the gate valve 9 and hold it in place and give direction thereto in its vertical movements.

A lever 11 pivotally mounted intermediate its ends is connected at one end by means of a link 12 with the gate valve 9 and is provided at its opposite end with a float 13 which automatically controls the movement of the gate valve according to the level of the water in the sewer pipe 1. Under normal conditions the gate valve 9 is open sufficiently to admit of the outflow of the sewage, but, under abnormal conditions tending to create a back-flow in the sewer and the flooding of the premises, the float 13 rises and the gate valve 9 is lowered, thereby cutting off the flow to the sewer and preventing back flow and a consequent flooding.

Lugs 14 project inwardly from the side walls of the frame or casing and are formed with vertical openings to receive the guide members of a substantially U-shaped hanger 15 upon which the lever 11 is pivotally mounted. Clamp screws 16 threaded into the lugs 14 secure the U-shaped hanger 15 in the required adjusted position. To install the form of check shown in the accompanying drawing in an existing sewer it is necessary to remove a portion from the top side of the pipe 1 to accommodate the frame or casing and the valve 9 and float 13. When the device is properly positioned it is made secure by means of the straps 7. Installation and adjustment of the parts may be facilitated by removing the cover 3. After the parts have been properly adjusted and the frame or casing made secure the cover 3 is replaced. Adjustment of the hanger 15 facilitates positioning of the valve and float to secure satisfactory results.

The numeral 17 denotes a centrifugal pump which is arranged to draw water from the house end of the sewer and discharge it into the sewer end beyond the valve 9. A suction pipe 18 is connected with the casing of the pump 17 and a discharge pipe 19 connects the outlet of the pump 17 with the frame or casing 2 of the attachment. A short pipe or nipple 20 is fitted in an opening formed in a side of the frame or casing 2. The discharge pipe 19 is connected to the nipple or pipe 20.

A head 21 is formed at one end of the pipe or nipple 20 and engages the inner side of the frame or casing 2. A nut 22 threaded upon the projecting end of the nipple or pipe 20 serves to clamp a wall of the casing 2 between it and the head 21, as shown most clearly in Figure 6 of the drawings. The face of the head 21 is inclined and provides a seat for a valve 23 which is pivoted at its upper end to the head 21. The face of the head 21 forming the seat for the valve 23 is inclined to insure a positive closing of the valve. A packing 24 is interposed between the head 21 and the wall of the casing or frame 2 to insure a close joint and prevent any leak.

A bracket 25 supports the pump 17 and is

secured to the flange 4 at one end of the frame or casing 2. An upright 26 is secured at its lower end to the frame or casing 2 and receives an electric motor 27 which is connected by means of a shaft 28 to the rotor of the pump 17. The circuit supplying current to the motor 27 is adapted to be closed by means of a switch 29 which is operable by means of the float 13 when the water rises in the sewer to a point to effect a closing of the valve 9. A vent 30 is provided in the top or cover 3 and consists of a body having a passage formed therein, the lower end of the passage opening through a side of the body and adapted to be closed when the said body is elevated to the limit of its upward movement. A rod 31 forms connecting means between the vent 30 and the movable member of the switch 29. An upright 32 attached to the top or cover 3 supports the switch 29.

When there is an abnormal rise of water in the sewer and the valve 9 is closed the premises are prevented from flooding by roof water discharging into the house end of the sewer by means of the pump 17 which draws water from the house end of the sewer and discharges the same into the end portion connected with the sewer and beyond the valve 9. When the water rises the float 13 also rises and lifting the vent 30 closes the switch 29 whereby the motor 27 is energized and the pump 17 operated. The vent 30 provides an escape for air when the water rises in the sewer. When the water is at its highest point the valve 9 is closed and the pump 17 operates to draw the water from the house side and discharge it into the sewer side of the soil pipe thereby preventing flooding of the premises from roof water and other discharge into the sewer. When the water subsides the float 13 descends and permits the vent lowering and the circuit to the motor being automatically broken. The pump therefore is automatic in action, both in the starting and stopping.

Having thus described the invention, I claim:

1. A sewer check comprising a frame having oppositely disposed flanges to overlap the sewer pipe and receive and confine a cementing material, means for securing the frame to the sewer, and a float operated valve mechanism within the frame for preventing flooding.

2. A sewer check comprising a frame, lugs projecting inwardly upon opposite side walls thereof, a substantially U-shaped hanger attachably connected with said lugs, a float operated lever mounted upon the hanger, and a gate valve having connection with the said lever to be automatically operated thereby.

3. A sewer check comprising an oblong frame, provided with a removable cover, a gate valve slidable against the inner side of

an end wall, and a float operated lever connected with the gate valve.

4. A sewer check comprising an elongated body open at its top and bottom, and having the bottom edge of its end walls curved and the bottom edge of its side walls oppositely beveled, and having flanges projecting outwardly from the end walls to overlap the sewer pipe, a cover for closing the top of the body, a gate valve slideable against the inner side of an end wall, a float operated lever mounted within the frame, and connecting means between said lever and the gate valve.

5. In combination with a sewer, a valve therein, a float connected with the valve to effect a closing thereof during an abnormal rise in the sewer, a pump adapted to draw water from the house side of the sewer and discharge it into the sewer side and automatically controlled by the opening and closing of the valve.

6. In combination with a sewer, a valve therein, a float connected with the valve, a pump connected with the sewer upon opposite sides of the valve, and a motor for the pump controlled by the action of the float.

7. In combination with a sewer, a movable vent therein, a valve adapted to cut off back flow in the sewer, a float for operating both the valve and vent, a pump having connection with the sewer upon opposite sides of the valve, and a motor for the pump adapted to be controlled by movement of the vent through the action of the float.

8. In a sewer, a valve therein, a movable vent, a float for controlling the valve and vent, a pump having connection with the sewer upon opposite sides of the valve, a second valve for preventing back flow through the pump, a motor for operating the pump, and a switch in the motor circuit adapted to be operated by means of the movable vent through the said float.

In testimony whereof I affix my signature.
